UNITED STATES PATENT OFFICE.

JAMES H. AUBLE AND JAMES L. AUBLE, OF CINCINNATI, OHIO, ASSIGNORS, BY DIRECT AND MESNE ASSIGNMENTS, OF TWO-NINTHS TO NATHAN HIRSCHBERG, OF CINCINNATI, OHIO, AND ONE-NINTH TO ALBERT L. WEINSTEIN, OF CINCINNATI, OHIO.

PRESS FOR FORMING SHEET-METAL FORMS.

Application filed October 13, 1920. Serial No. 416,717.

To all whom it may concern:

Be it known that we, JAMES H. AUBLE and JAMES L. AUBLE, citizens of the United States, and residents of the city of Cincinnati, in the county of Hamilton and State of Ohio, have invented certain new and useful Improvements in Presses for Forming Sheet-Metal Forms, of which the following is a full, clear, and exact description, reference being had to the accompanying drawings, forming part of this specification.

Our invention relates to machines for forming sheet metal blanks by dies and punches in which the articles may be formed by a series of dies in one continuous operation instead of in a series of separate independent operations.

In the attempts that have heretofore been made to treat sheet metal in one continuous operation, a series of dies have been provided, each set arranged to collapse after its work has been accomplished and in order to provide for such operation it has heretofore been found necessary to hold the parts under spring tension and difficulty has been experienced in properly regulating the spring tension for the shifting of the dies for successive operations. It is the object of our present invention to provide a construction in which the employment of springs shall be obviated and the die sections shall be connected together positively and operated by screw threaded engagement with each other, whereby they may be positively actuated at the desired intervals with uniformity and accuracy.

In the drawings—

Figure 1 is a central, longitudinal section of the two sets of dies partly broken away to show portions of the dies in elevation at the commencement of the operation.

Figure 2 is a similar view at the end of the first operation.

Figure 3 is a similar view at the end of the second operation.

Figure 4 is a similar view at the end of the third operation.

Figure 5 is a perspective view of the shaper head partly in section.

Figure 6 is a perspective view of the housing or casing for the upper set of dies.

Figure 7 is a similar view for the lower housing.

Figure 8 is a similar view of the ram head.

Figure 9 is a perspective view of the tension bolts for holding and guiding the upper set of dies.

Figure 10 is a similar view of the plunger for removing the finished article.

Figure 11 is a perspective view of the lower rotatable dies.

Figure 12 is a similar view partly broken away of the outermost upper die.

Figures 13 and 14 are similar views of the die shown in Figure 11 with different portions broken away.

Figures 15, 16 and 17 are perspective views of the parts making up one of the inner dies of the upper series.

Figures 18, 19 and 20 are similar views of another of these dies.

Figures 21, 22 and 23 are similar views of the parts making up the inner shaft about which the parts operate.

Figure 24 is a perspective view, partly broken away and on a somewhat enlarged scale of one of the dies of the upper series.

Figure 25 is a perspective view of one of the collapsible rings.

As illustrated we have shown a simple construction for forming a cylindrical shell although it will be understood that any desired shape of dies may be employed. Also we have shown three sets of forming dies while the number may be increased or diminished as desired. The male dies comprise an upper and a lower set which are interlocked to slide and rotate with reference to each other as the female die mounted on the ram of the press is advanced gradually in one continuous operation to make the required drafts on the metal.

The bolster plate 1 of the press has securely bolted thereto a lower housing or casing 2 and an upper casing 3. Centrally mounted and held rigid in the bottom plate 6 of the housing by the nut 5 is an upright shaft 4 around which the male dies slide and rotate.

The ram head 7 carries the female die or shaper 8 which is provided with the vari-

ous shoulders 9 and 10 and the recess 11 for forming the blank into the desired shape in connection with the male dies.

- The shaper 8 is suspended from the ram 5 head by the tension bolts 12, 12. The bolts or rods extend through holes in the base of the ram head and are secured by nuts 13, 13 to a plate or bar 14 which is adapted to slide in a vertical slot 15 in the ram head. 10 The lower ends of these rods 12 extend down through holes 16, 16, in the housing or casing 3 which encloses the upper set of the male dies and which casing is rigidly mounted on the bolster 1 by the bolts 18. 15 The lower ends of the tension bolts 12 are provided with heads 20, 20, which are adapted to slide in vertical grooves 21 in the inner wall of the casing and the heads also project inwardly and engage under the 20 upper end of the outermost male die, which is also provided with vertical slots to permit the heads to slide therein.

Mounted in the central recess 11 in the shaper is a plunger plate 22 which is secured 25 to the bar 14 by the bolts 23 and nuts 24.

The housing 3 is provided with a horizontal slot 25 through which the blank 26 to be drawn is passed for the action of the dies.

The outer edge 27 of the shaper in cooperation 30 with the edge 28 of the casing immediately below the slot forms a cutting edge for trimming off the blank as will be described.

Located within the casing 3 are a series of male dies 29, 30 and 31 arranged to telescope 35 within each other, but prevented from rotating with reference to each other by keys and key-ways indicated at 32 and 33. These dies 29, 30 and 31 of this upper set are supported on and in screw threaded engagement with 40 a lower set of supporting die members 34 and 35. The upper die 29 which with its upper surface 36 presents a support and clamping surface for the blank to be formed is provided with exterior screw threads at an 45 angle of say 45 degrees which are in engagement with the die member 34. The other supporting die member 35 is provided with screw threads at a similar angle for both its outside and inside surfaces and the die 30 is 50 screw threaded to engage the outer surface and the die 31 to engage the inner surface of the die support 35. The screw threads for the inner members are so arranged that the engagement does not take place however in 55 the first instance but only after a partial rotation of the respective dies. The upper male dies being keyed together and to the fixed control shaft 4 do not rotate, but as pressure is brought to bear by the shaper 60 head the outermost die 29 descends which causes the die support member to rotate and with it the inner support 35. The male and female screws are so disposed that the inner telescope dies 30 and 31 will not descend but 65 will rest on top of the supporting member

until the screw threads are brought into alignment and thus in turn the inner dies will also descend.

The upper and active ends of the male dies 30 and 31 over which the blank is rolled 70 and folded are each provided with a flanged section 37 for the die 30 (Figures 17 and 24) and 38 (Figure 20) for the die 31. These sections are screw threaded into the bodies of their respective dies and around the upper ends underneath the flange, we provide an expansion coil of supporting wire 39 for die 30 and 40 for die 31. This construction is illustrated in Figures 15, 16 and 17 for one die and in Figures 18, 19 and 20 for the other.

The object of this construction is to provide a compressible surface over which to roll the blank under treatment and thus prevent undue strain on the metal and to obtain 85 a smooth unwrinkled surface for the blank, causing a rolling and preventing a drawing or stretching action and taking care of the thickening or flattening of the metal.

The various details of the construction 90 can be more readily understood by a consideration of the mode of operation in the treatment of the blank from its introduction into the press.

In Figure 1 the press is shown ready for 95 the introduction of the metal and the initial stroke of the ram head 7 carrying the shaper 8. The metal to be blanked is inserted in the slot 25 and the head brought down. The outside edge 27 and the edge 28 in the inside 100 of the housing 3 form cutting edges to cut the blank to the size or shape desired and the metal during the cutting is clamped between the outside portion of the shaper and the upper surface of the die 29. As heretofore described the lower end of the die 29 is in screw threaded engagement with the supporting member 34 and the downward pressure of the shaper causes this member 34 to rotate. The members 34 and 35 are united 105 together by the base 40 and the member 35 rotates with the member 34. The upper member 29, therefore, descends and the blank is rolled and formed over the die 30 into the position shown in Figure 2. During 110 this movement the dies are held in perfect threaded contact, the inner dies being in contact on the upper end of member 34 in the offsets of the thread. The heads 20 on the lower ends of the tension rods 12 descend in the slots 21 in the housing 3 and the slots 41 (Figure 12) in the die 29. By the time the first form is rolled the supporting member 35 has rotated sufficiently to allow the female thread 42 on the inner surface of 115 the die 30 to operate with the male thread 43 on the outer surface of member 35. The die 30 will, therefore, begin to descend and by reason of the threads will be pulled down and only at the rate permitted by the screw 120

threads and the dies will assume the position shown in Figure 3 and the second form will be given the blank.

The ram still descending, the member 35 will be rotated sufficiently to allow the male thread 44 on the outer surface of die 31 to operate with the female thread 45 on the inner surface of the member 35 and the die 31 will begin to descend. The upper end of the 10 shaft 4 then becomes the male die. This shaft is provided with the head 43 having a stem 47 seated in a central opening in the shaft. In addition to utilizing this innermost male die as merely a forming die, we 15 can also make provision in the final operation for pressing screw threads on the inner surface of the finished blank. To accomplish this we form a cone 48 on the upper end of the shaft 4 and mount on this cone 20 an expansion cutting tap formed of a spiral coil 50 to be seated on the core. The flange or projecting portion of the head 46 bears upon this expansion tap and this pressure slides the tap towards the base of the cone 25 thus pressing the screw threads in the finished blank.

At the completion of the stroke of the head the dies will be in the position shown in Figure 4. During the final movement the 30 plunger 22 has been pushed upward into the base of the inner socket in the shaper and this has carried the bar 14 into this upper end of the slot in the ram head as shown in Figure 4. This movement of the bar 14 also 35 retracts the tension rods 12 and at the completion of the down stroke the lugs 20 have been drawn upwardly ready to engage the die 29 at the upper end of the slot 41.

The blank has now been completely 40 formed in one continuous operation and the return stroke of the ram in the first place pulls the bar 14 back to its position as shown in Figures 1, 2 and 3. The effect of this is to causes the plunger 22 to push the finished 45 blank from the forming die so that it can be removed. The draft on the outermost die 29 by the heads in the tension rods then causes the supporting members to rotate in the opposite direction and by reverse movement 50 the various dies are brought back to their original normal position ready for the next operation.

It will be noted that in forming the blank with our construction in which the dies are 55 held positively during the successive operations and after a die has served its purpose and is caused to telescope to bring into action the next succeeding die, that the movement is positive and that by the screw 60 threaded engagement the die is gradually withdrawn in exact proportion to the advance of the ram head so that pressure is always maintained on the blank throughout the series of operations. Instead of the dies 65 when ready to be released being held by

spring pressure and allowed to collapse, the die is positively withdrawn and at the same rate as the shaper advances. This is a point of great importance in our present construction for the reason that in this way the metal blank may be rolled, as it were, into the form desired and the liability of the metal to wrinkle is reduced to a minimum. Where a wrinkle forms, the strength of the metal is increased so that it is extremely difficult in a 70 successively operating machine to smooth out the wrinkles. Whereas with our construction, the pressure never being released, the metal can be rolled into shape without the formation of wrinkles. 75

Having thus described our invention, what we claim as new and desire to secure by Letters Patent, is:—

1. In an apparatus of the character specified a forming die comprising a non-rotatable slidable member and a rotatable actuating member adapted to make screw threaded engagement with the slidable member and means for rotating the rotatable member to bring said screw threaded portions into engagement to positively withdraw the forming die. 85

2. In an apparatus of the character specified a forming die comprising a non-rotatable slidable member and a rotatable actuating member adapted to make screw threaded engagement with the slidable member, a supporting member for the blank to rotate the rotatable member to bring said screw threaded portions into engagement to 90 positively withdraw the forming die. 95

3. In an apparatus of the character specified, telescoping dies comprising outer and inner members adapted to slide but not to rotate with reference to each other with a 105 cooperating rotatable supporting member with which the dies make successive screw threaded engagement to permit the telescoping of said dies in succession.

4. In an apparatus of the character specified, telescoping dies, comprising outer and inner members adapted to slide but not to rotate with reference to each other with a 110 cooperating rotatable supporting member with which the dies make successive screw threaded engagement to permit the telescoping of said dies in succession, and means for rotating the rotatable member to bring said screw threaded portions into engagement. 115

5. In an apparatus of the character specified, telescoping dies, comprising outer and inner members adapted to slide but not to rotate with reference to each other with a 120 cooperating rotatable supporting member with which the dies make successive screw threaded engagement to permit the telescoping of said dies in succession, and a blank 125 supporting member for rotating the rotatable member to bring said screw threaded portions into engagement. 130

portions into engagement to positively withdraw the forming dies.

6. In an apparatus of the character specified telescoping dies comprising outer and inner members adapted to slide but not to rotate with reference to each other, a co-operating rotatable supporting member with which the dies make successive screw thread-

ed engagement and an inner forming die with a cone shaped support therefor and an ¹⁰ expansion cutting tap intermediate the die and support whereby a blank may be formed and internally threaded in one continuous operation.
